ENGINE RADIATOR

Auguste Louis René Bernard, deceased, late of
Rueil-Malmaison, France, by Renée Bernard,
née Bournonville, executor, Paris, France

Application January 25, 1935, Serial No. 3,529
In Belgium February 2, 1934

7 Claims. (Cl. 123—174)

The present invention relates to motors including a cooling jacket connected with a heat radiating element. It is more especially, although not exclusively, concerned with motors of this kind in which said heat radiating element is a steam condenser.

The object of the present invention is to provide improved motors of this type which are better adapted to meet the requirements of practice.

The essential feature of the present invention consists in so devising the heat radiating element to be provided in motors of the kind above referred to that this element can be readily displaced, either for cleaning it or for making it possible to reach organs that are normally covered by said element.

This and other features of the present invention will be more specifically described in the following specification.

A preferred embodiment of the present invention will be hereinafter described, with reference to the accompanying drawing, given merely by way of example, and in which:

Fig. 1 is a vertical axial sectional view of a motor according to the present invention and consisting of a vertical single cylinder internal combustion engine;

Fig. 2 is a corresponding side view;

Fig. 3 is a horizontal sectional view on the line III—III of Fig. 2.

According to the present invention, the whole of the engine, with the exception of the cooling system thereof, is made of any conventional or other type.

As for the cooling system it includes a cooling jacket 1 surrounding the engine cylinder and provided with suitable inlet and outlet orifices, and a heat radiating element 2 adapted to operate with said jacket 1.

According to the present invention, this heat radiating element 2 is so devised that it may be easily displaced, either for cleaning it or for making it possible to reach organs that are normally covered by said element 2.

Accordingly, this heat radiating element is secured to the engine parts through securing means adapted to be quickly brought out of action and adapted to normally apply the inlet and outlet pipes of said heat radiating element in a fluid-tight manner against the above mentioned inlet and outlet orifices of the cooling jacket, respectively. Advantageously the inlet and outlet orifices will be juxtaposed to each other, so as to

permit the grouping together of the packing means to be used.

Of course, according to the present invention, the heat radiating element and the cooling jacket of the engine (or any intermediate organs carrying the orifices to be connected together) can be so arranged that these parts are wholly independent of one another when the securing means above referred to are in inoperative position.

But preferably, according to the arrangement shown by the drawing, these parts are always connected together, through any suitable means, and for instance, as shown by Fig. 1, through hinges 3 about which the heat radiating element 2 can pivot.

In this embodiment of the invention, the securing means are advantageously disposed close to the orifices of the heat radiating element to permit a secure tightening of these orifices to the inlet and outlet orifices of the cooling jacket.

The present invention is particularly interesting in the case of engines the heat radiating element of which is a condenser located above the level of the cooling liquid.

In this case, the condenser should be provided with a steam inlet orifice 4 and an outlet tube 5 for condensed water. Advantageously, this pipe 5 is arranged to pass through the steam outlet orifice which is then provided at the top of cooling jacket 1. For this purpose, said tube 5 is provided with a prolonged part 6 made of such a length that it dips in the cooling liquid present in the jacket as long as the level of said liquid is higher than the minimum level *m* (Fig. 1).

It is therefore sufficient to provide a single packing device between the condenser and the cooling jacket, since each of these parts includes only one orifice. For instance, as shown in the drawing, this packing device consists merely of a rubber or similar ring 7 adapted to be held between the edges of the orifices of the cooling jacket and the condenser, respectively.

With these arrangements, a very simple embodiment can be devised when it is desired to arrange, according to the invention, a vertical single-cylinder internal combustion engine the condenser of which is disposed substantially horizontally above the engine in such manner that an air stream produced by any suitable fan is caused to flow through said condenser.

Advantageously, this embodiment of the invention is made as follows:

The condenser consists of a nest of tubes in the shape of a flattened arc extending between a steam header 8 and a condensed water header 55

9, the whole being surrounded by a casing 10. This casing, made for instance of metal sheets, is provided with apertures adapted to put into communication with the atmosphere the space 5 located above the nest of tubes, while the space located underneath this nest of tubes communicates with the intake tube of the fan above mentioned.

This condenser is arranged in such manner 10 that headers 8 and 9 are disposed horizontally above the cylinder head, on either side of the latter, the nest of tubes thus covering said cylinder head.

The condensed water header 9 is pivoted to the 15 cylinder head through hinges 3.

The bottom of header 8 carries the steam inlet orifice 4.

A tube 5, leading from header 9 to said orifice 4, carries the prolonged part 6 above mentioned. 20 Preferably, this tube 5 is so arranged that, when the condenser is in its working position, said tube is sufficiently inclined for ensuring the flow of condensed water to said part 6.

At the upper part of the cooling jacket that 25 surrounds the cylinder head, there is provided a steam outlet orifice 11 of a size corresponding to that of orifice 4 and disposed opposite said orifice 4. Advantageously, packing member 7 is supported about said orifice 11.

30 Between header 8 and the cylinder head, there are provided securing means adapted to be quickly brought out of action, said means consisting for instance of a stirrup 12 pivoted to header 8 and carrying a securing screw 13 having a milled head, adapted to bear against a projecting part 14 of the jacket.

Although casing 10 may be made rigid with condenser 2 so that both parts can pivot together, for instance through an angle of 90°, about hinges 40 3, it is believed more advantageous to provide, for each of these parts, a separate articulation, whereby it is possible, if so desired, to lift casing 10 without displacing condenser 2.

For this purpose, said casing may be, for instance pivoted, independently of the condenser, about hinges coaxial to hinges 3.

It is also obvious that casing 10 might be carried in a removable manner by the condenser without being connected thereto through hinges.

50 This casing may, for instance, surround the condenser at the upper part and also on the sides and it may also be joined with other casing elements 15 disposed on the front and on the rear of the condenser. But in any case casing 10 is 55 so arranged as to compel air to flow through the nest of tubes.

It will be readily understood that, owing to the arrangements that have been above described, when the condenser is swung into the open position, 60 it is possible to reach the organs located underneath it on the cylinder head, such for instance as injector 16, if the latter is so positioned.

This will make it possible to devise the upper part of the engine without being limited by the 65 fact that some organs cannot occupy certain positions in which they could not be reached, due to the presence of the condenser, when said condenser is permanently fixed to the engine. For instance, the injector 16 can be placed at the 70 center of the cylinder head, immediately under the nest of tubes of the condenser, pipe 5 being, of course, in this case, bent so as to leave room for said injector.

With this arrangement, it will be advantageous 75 to provide the condenser (and for instance the

nest of tubes of said condenser) with a kind of bell 17 so arranged that, when the condenser is in working position, said bell covers the injector and its edges fit against the portion of the surface of the jacket that surrounds the injector. 5

Said injector is then enclosed in a chamber into which dust contained in the air that flows through the condenser cannot enter.

Of course, this bell moves together with the condenser and does not in any way prevent access 10 to the injector when the condenser is swung up in the open position. As for tube 5, it is advantageously disposed on the outside of said bell.

The operation and the advantages of the system above described are believed to result clearly 15 from the preceding description.

It should be noted that the organs located under the heat radiating element are not necessarily an injector, as diagrammatically shown at 16, but might consist of valves, with their springs, their 20 control organs, etc.

In a general manner, while I have, in the above description, endeavoured to disclose what I deem to be practical and efficient embodiments of the present invention, it should be well understood 25 that I do not wish to be limited thereto as there might be changes made in the arrangement, disposition and form of the parts without departing from the principle of the present invention as comprehended within the scope of the appended 30 claims.

What I claim is:

1. In combination with a motor, a cooling jacket adapted to contain a boiling liquid provided with a steam outlet orifice, a condenser having an inlet orifice adapted to register with said steam outlet orifice, a condensed liquid outlet pipe carried by said condenser adapted to extend through said steam outlet orifice so as to open into said jacket, means for removably fixing said condenser 40 to said motor so that said inlet orifice of the condenser is applied against the outlet orifice of the cooling jacket, and means for forming a fluid-tight joint between these orifices.

2. In combination with a motor, a cooling 45 jacket adapted to contain a boiling liquid provided with a steam outlet orifice, a condenser hinged to said motor provided with an inlet orifice adapted to register with said steam outlet orifice, a condensed liquid outlet pipe carried by 50 said condenser adapted to extend through said steam outlet orifice so as to open into said jacket, means for removably fixing said condenser to said jacket in the closed position so that said inlet orifice of the condenser is applied against the steam outlet orifice of the cooling jacket, and means for forming a fluid-tight joint between these orifices.

3. In combination with a motor, a cooling 60 jacket adapted to contain a boiling liquid provided with a steam outlet orifice, said jacket being rigid with said motor and surrounding it, a condenser, including a steam header, a condensed water header, and a nest of tubes extending between said headers, hinged to said jacket, said steam header being provided with an inlet orifice adapted to register with said steam outlet orifice when the condenser is swung into the closed position, an outlet pipe extending from said condensed water header into said inlet orifice of the steam header, a prolonged part of said pipe adapted to penetrate through said steam outlet orifice into said cooling jacket, means for removably fixing said condenser to said jacket in the closed position so that said inlet orifice of 70 75

the condenser is applied against the steam outlet orifice of the cooling jacket, and a rubber ring carried by said jacket along the edge of said steam outlet orifice for forming a fluid-tight joint with the inlet orifice of the condenser.

5. A system according to claim 3 further including a casing surrounding said nest of tubes and pivotally connected to said jacket.

10. A system according to claim 3 in which the upper part of the motor carries in its central part an organ to be protected against dust and other impurities, which further includes a bell shaped cover carried by said condenser adapted to fit against the top of said motor so as to surround 15 said organ, when the condenser is swung down into its closed position.

15. In combination with a motor, a cooling jacket adapted to contain a boiling liquid provided with a steam outlet orifice, a condenser hinged to said motor provided with an inlet orifice adapted to register with said steam outlet or- 20

ifice, means for carrying back condensate into said cooling jacket and means for removably securing said condenser to said jacket in closed position so that said inlet orifice of the condenser is applied against and secured to the steam outlet orifice of the cooling jacket.

25. In combination with a motor, a cooling jacket adapted to contain a cooling liquid and provided with an outlet orifice, a heat radiating element hinged to said motor and provided with an inlet orifice adapted to register with said outlet orifice, means for carrying back the liquid contained in said radiating element to said jacket, and means for removably securing said radiating element to said jacket in closed position so that 15 said inlet orifice of said radiating element is applied against and secured to the outlet orifice of the cooling jacket.
